UNITED STATES PATENT OFFICE.

FRANKLIN P. BURNHAM, OF MIDDLETOWN, OHIO, ASSIGNOR TO THE MIAMI CYCLE AND MANUFACTURING COMPANY, OF SAME PLACE.

DESIGN FOR A REAR FORK FOR BICYCLES.

SPECIFICATION forming part of Design No. 30,914, dated May 30, 1899.

Application filed April 21, 1897. Serial No. 633,194. Term of patent 14 years.

To all whom it may concern:

Be it known that I, FRANKLIN P. BURNHAM, a citizen of the United States, residing at Middletown, in the county of Butler and State of Ohio, have invented and produced a certain new and useful Design for a Rear Fork for Bicycles, of which the following is a specification.

My invention relates to a new and original design for a rear fork for bicycles and is illustrated in the accompanying drawings, wherein—

Figure 1 is a side view of the fork for bicycles embodying my invention. Fig. 2 is a plan view of the fork shown in Fig. 1.

In the embodiment of my design I form the rear fork A of the bicycle with an outward bend or bulge A' back of the crank-hanger sleeve A² and opposite the point occupied by the tire of the rear wheel when in position. 20

The essential feature of my design is a rear fork for bicycles provided with a bulge or bend back of the crank-hanger sleeve.

I claim—

The design for a rear fork for bicycles as 25 herein shown and described.

FRANKLIN P. BURNHAM.
